UNITED STATES PATENT OFFICE.

THEODOR BUCHHOLZ, OF BERLIN-ZEHLENDORF-WEST, GERMANY.

RAIL FASTENING.

Application filed January 15, 1926, Serial No. 81,562, and in Germany April 24, 1925.

This invention relates to a method of fixing rails for supporting heavy wheel-loads on iron, wooden or concrete sleepers.

The object of the present invention is to provide an arrangement which is very simple to manufacture and to fix and ensures absolutely secure bearing of the rail on the sleeper. The fixing of the rails is to be effected by means of a sole plate and this sole plate is to have the peculiarity, that the fixing on the sleeper is independent of the fixing of the rail on the sole plate, so that the rails may be released without its being necessary to release the plate from the sleeper. This feature is of particular importance for iron and for concrete sleepers and in the case of wooden sleepers has the advantage that the holes for the sleeper screws may be made beforehand and be impregnated when the sleeper is being treated. A further feature of the sole plate is, that it has no holes besides the holes for the coach screws for the wooden sleepers, so that there will be no accumulation of water or dirt under the plate which would tend to destroy the sleeper.

The invention consists substantially in this that a sole plate is used which lies flat on the sleeper, is preferably made by rolling and is provided with upwardly extending ribs, projections or the like for the reception of the screws holding the clips. For this purpose the ribs or projections are provided with recesses, into which the clip screws can be inserted. Preferably the recesses should not extend right through the sole plate, the ribs or projections providing the means for holding the clip screws.

In the accompanying drawing two constructional forms of the invention are shown by way of example, in Figs. 1 and 2 in transverse section and plan view, as applied to a wooden sleeper, and in Fig. 3 as applied to an iron sleeper.

Figs. 4 to 17 show various details, Fig. 4 being a section on line A—B of Fig. 2,

Figs. 5, 6 and 7 a transverse section, plan view and side view of the sole plate,

Figs. 8 and 9 the T-headed bolts for fixing the clip,

Figs. 10 and 11 the clips,

Figs. 12, 13, 14, 15, 16 and 17 various views of the gauge adjusting clip.

As will be seen from Fig. 1, the new fixing means consists of a sole-plate α which is pro-

vided with ribs or projections b . The sole-plates are fixed on the wooden sleeper c by means of screws d . Between the ribs or projections b lies the rail i . The rail is held down on the sole plate by means of clips h which are drawn down tightly on the sole plate by means of the bolts f . The bolts f engage in the ribs b preferably by their heads being inserted in suitable recesses in the ribs. Gauge adjusting members are introduced as required between the ribs and the base of the rail.

The side of the ribs b facing the rail is preferably slightly inclined to the sole plate with the object of preventing the gauge adjusting members which rest against the ribs from slipping upwards. On straight parts of the track the distance apart of the ribs or projections b may be made such that it corresponds to the width of the rail base, in which case no gauge adjusting members are required.

The fixing bolts f are made in the form of T-headed bolts. The head is either rectangular or trapezoidal. Preferably the head z of the bolts has a curved bearing surface as shown in Figure 4. In the latter case the recesses in the ribs of the sole plate need only be very low so that the ribs themselves and the entire plate will be relatively low. With this form of head the bolts are capable of tilting slightly in a direction parallel to the rail, the width of the recess at the top of the projections b being slightly greater than the diameter of the shank of the bolt so as to enable the bolt to rock.

Through the head bearing against straight surfaces the bolt is prevented from turning. The construction of the sole plate is shown in detail in Figures 5, 6 and 7. The plate α is provided with ribs b which are inclined inwards and these ribs are provided with recesses s , into which the heads z of the screw bolts fit. Figures 8 and 9 show a preferred form of the bolts in side elevation and plan view, Figure 9 showing that the bolt heads are narrow, corresponding to the width of the ribs.

The clips h , which are screwed down firmly on to the sole plate by means of the bolts f and thereby firmly hold the rails in position, bridge over the ribs or projections b . Their shape is shown in Figures 10 and 11. The upper part of the clips is somewhat narrower than the width of the feet for facilitating the screwing together of the

various parts and in order to prevent the upper part of the clips bearing against the fish plates or the fish bolts.

For providing a particularly good, wide bearing surface for the feet of the clips on the base of the rail and the sole plate, when the clips are held down by the bolts, the bearing faces of the feet of the clips are given different inclinations, as shown in Figure 10.

For adjusting the gauge so-called gauge plates are used, which are shown in Figures 12 to 17. They consist of narrow strips *m*, the surface *x* of which facing the ribs or projections is inclined, for the purpose of preventing the strips from slipping up accidentally. At the ends of the upper edge the gauge plates are provided with small projecting parts *n*. The recess lying between the said projections *n* serves for the reception of the clips so that the latter are prevented from slipping sideways.

For providing means for adjusting the gauge, the gauge plates are made as usual in several thicknesses. On the sides projections or lugs *u* may be provided (Figs. 15, 16 and 17), which engage in the recesses in the ribs and thereby prevent the gauge plates from slipping out and also securing the clip bolts at the correct distance from the base of the rail.

The gauge may also be adjusted by means of the clips *h*, if the clips are provided, as shown in dotted lines in Fig. 10 with downwardly directed lugs *o*, of a suitable width, which lie between the rail base and the ribs (cf. Fig. 3).

When the new sole plate is to be fixed on an iron sleeper the sole plate *a*, as there are no sleeper screws, is made correspondingly narrower (cf. Fig. 3) and is fixed in any suitable manner on the iron sleeper *c*, preferably by being welded on it.

What I claim is:

1. A rail fastening, comprising a rail seat in combination with rib-like members, clips capable of bridging the said members, bolts for holding down the said clips and a recess in each rib-like member, into which the bolts can be inserted from the side, the bolts lying between the clip and the base of the rail, whereby they are held in position in the said recesses, as set forth.

2. A rail fastening, comprising a rail seat in combination with rib-like members, clips capable of bridging the said members, bolts for holding down the said clips, a recess in each rib-like member, into which the bolts can be inserted from the side, and a gauge adjusting member capable of being inserted between the base of the rail and the rib-like member, the bolts lying between the clip and the said gauge adjusting member, whereby they are held in position in the said recesses, as set forth.

3. A rail fastening, comprising a rail seat in combination with rib-like members inclined towards one another, clips capable of bridging the said members, bolts for holding down the said clips and a recess in each rib-like member, into which the bolts can be inserted from the side, as and for the purpose set forth.

4. A rail fastening, comprising a rail seat in combination with rib-like members having their sides facing the rail slightly undercut, clips capable of bridging the said members, bolts for holding down the said clips and a recess in each rib-like member, into which the bolts can be inserted from the side, as and for the purpose set forth.

5. A rail fastening, comprising a rail seat in combination with rib-like members, clips capable of bridging the said members, T-headed bolts for holding down the said clips and an undercut recess in each rib-like member, into which the bolts can be inserted from the side, the faces of the head bearing against the undercut parts of the recess being curved for enabling the bolts to tilt in a direction parallel to the rail, as set forth.

6. A rail fastening, comprising a rail seat in combination with rib-like members, clips capable of bridging the said members, T-headed bolts for holding down the said clips and an undercut recess in each rib-like member, into which the bolts can be inserted from the side, the faces of the head bearing against the undercut parts of the recess being curved for enabling the bolts to tilt in a direction parallel to the rail and curved, as set forth.

7. A rail fastening, comprising a rail seat in combination with rib-like members having their sides facing the rail slightly undercut, clips capable of bridging the said members, bolts for holding down the said clips, a recess in each rib-like member, into which the bolts can be inserted from the side and a gauge adjusting member capable of being inserted between the base of the rail and the rib-like member, the bolts lying between the clip and the said gauge adjusting member, whereby they are held in position in the said recesses, the said gauge adjusting members being tapered to correspond to the undercut side of the rib-like member, as set forth.

8. A rail fastening, comprising a rail seat in combination with rib-like members having their sides facing the rail slightly undercut, clips capable of bridging the said members, bolts for holding down the said clips, a recess in each rib-like member, into which the bolts can be inserted from the side and a gauge adjusting member capable of being inserted between the base of the rail and the rib-like member, the bolts lying between the clip and the said gauge ad-

- justing member, whereby they are held in position in the said recesses, the said gauge adjusting members being tapered to correspond to the undercut side of the rib-like member, and having a portion of their upper edge cut away so as to form an upwardly projecting lug at either end capable of embracing the clip and preventing its lateral displacement, as set forth.
10. 9. A rail fastening, comprising in combination a rail seat with rib-like members between which the rail can rest, clips for holding down the rail, bolts for holding down said clips and transverse recesses provided in said rib-like members into which the bolts can be inserted, said recesses extending right across the rib-like members but not extending through the rail seat itself.
15. 10. A rail fastening, comprising in combination a rail seat with rib-like members between which the rail can rest, clips for holding down the rail, bolts for holding down said clips and transverse recesses provided in said rib-like members into which the bolts can be inserted with the heads of the bolts lying between the clip and the base of the rail so as to be held in position in said recesses.
20. 11. A rail fastening comprising in combination a rail seat with rib-like members between which the rail can rest, clips for holding down the rail, bolts for holding down said clips, transverse recesses provided in said rib-like members into which the bolts can be inserted, said recesses extending right across the rib-like members but not extending through the rail seat itself and gauge adjusting members adapted to be inserted between the rib-like members and the base of the rail, as set forth.
25. 12. A rail fastening comprising in combination a rail seat with rib-like members between which the rail can rest, clips for holding down the rail, bolts for holding down said clips, transverse recesses provided in said rib-like members into which the bolts can be inserted, said recesses extending right across the rib-like members but not extending through the rail seat itself and gauge adjusting members consisting of narrow parallel bars adapted to be inserted between the rib-like members and the base of the rail, as set forth.
30. 13. A rail fastening, comprising in combination a rail seat with rib-like members between which the rail can rest, said rib-like members having their sides facing the rail slightly receding, clips for holding down the rail, bolts for holding down said clips, and transverse recesses provided in said rib-like members into which the bolts can be inserted, said recesses extending right across the rib-like members but not extending through the rail seat itself.
35. 14. A rail fastening, comprising in combination a rail seat with rib-like members between which the rail can rest, said members having their sides facing the rail slightly receding, clips for holding down the rail, bolts for holding down said clips, transverse recesses provided in said rib-like members into which the bolts can be inserted, said recesses extending right across the rib-like members but not extending through the rail seat itself, and gauge adjusting members adapted to be inserted between the rib-like members and the rail and having a wedge-shaped cross-section, as and for the purposes set forth.
40. 15. A rail fastening, comprising in combination a rail seat with rib-like members between which the rail can rest, clips for holding down the rail, bolts for holding down said clips, transverse recesses provided in said rib-like members into which the bolts can be inserted, said recesses extending right across the rib-like members but not extending through the rail seat itself, and gauge adjusting members adapted to be inserted between the rib-like members and the rail, said gauge adjusting members having projections capable of engaging the clips, for the purpose set forth.
45. 16. A rail fastening comprising in combination a rail seat with rib-like members between which the rail can rest, clips for holding down the rail, recesses provided in said clips, bolts for holding down said clips, transverse recesses provided in said rib-like members into which the bolts can be inserted, said recesses extending right across the rib-like members but not extending through the rail seat itself, and gauge adjusting members adapted to be inserted between the rib-like members and the rail, said gauge adjusting members having projections capable of engaging the recesses in the clips, as set forth.
50. 17. A rail fastening, comprising in combination a rail seat with rib-like projections between which the rail can rest, clips for holding down the rail, bolts for holding down said clips, said bolts having hammer heads with bearing surfaces which are inclined with respect to the shank, undercut transverse recesses provided in said rib-like members into which the bolts can be inserted, and in which the bolts are capable of tilting, said recesses extending right across the rib-like members but not extending through the rail seat itself, as set forth.
55. 18. A rail fastening, comprising in combination a rail seat with rib-like members between which the rail can rest, clips for holding down the rail, bolts for holding down said clips, said bolts having heads with curved bearing surfaces, and undercut transverse recesses provided in said rib-like members into which the bolts can be inserted,

said recesses extending right across the rib-like members but not extending through the rail seat itself, as and for the purpose set forth.

5 19. A rail fastening as set forth in claim 1, having the rail seat integral with an iron sleeper.

20. A rail fastening as set forth in claim 1, having the rail seat welded to an iron sleeper so as to be integral therewith.

In testimony whereof I have signed my name to this specification.

THEODOR BUCHHOLZ.
